UNITED STATES PATENT OFFICE.

CARL F. WILSON, OF BAY CITY, MICHIGAN.

WALKING-MACHINE.

1,296,893.

Specification of Letters Patent. Patented Mar. 11, 1919.

Application filed July 8, 1916. Serial No. 108,147.

To all whom it may concern:

Be it known that I, CARL F. WILSON, a citizen of the United States of America, residing at Bay City, in the county of Bay 5 and State of Michigan, have invented certain new and useful Improvements in Walking-Machines, of which the following is a specification.

This invention relates to movable supporting devices for dredging and other like machinery.

One object of the invention is to provide a moving support for dredges and the like which does not require a track upon which 15 to move it.

An other object resides in the provision of means for giving the support a step by step movement to follow the work upon which it is engaged.

20 A further object resides in the provision of a machine or device of the nature stated, embodying means for moving the machine backward through the instrumentality of the mechanism used for forward movement.

25 A still further object resides in the provision of a plurality of cables and pulleys arranged in a novel manner for accomplishing the above objects and results.

With the above and other objects in view, 30 the present invention consists in the combination and arrangement of parts herein-after more fully described, illustrated in the accompanying drawings, and particularly pointed out in the appended claims, it being 35 understood that changes may be made in the form, size, proportion and minor details without departing from the spirit or sacrificing any of the advantages of the invention.

40 In the drawings:

Figure 1 is a plan view of my preferred device.

Fig. 2 is a side elevation thereof.

Fig. 3 is a side elevation showing the support elevated for moving forward.

Fig. 4 is a similar view showing the main frame elevated and the relative position of the skids when the machine is moved forward.

50 Fig. 5 is a partial rear elevation.

Fig. 6 is a detail side elevation of the drums upon which the cables used for moving the skids forward and rearward, are wound.

55 Fig. 7 is a detail side elevation of the

drums upon which the lifting cables are wound.

Fig. 8 is a sectional elevation of the clutch used, and

Fig. 9 is an end elevation of the clutch. 60 In the drawings, a pair of spaced main skid members 1 are provided upon which are mounted at each end thereof, the brackets 2 for supporting the main frame members 3 and 4, to which are secured the various 65 transverse and longitudinal beams 5, located between the said members. Upon these beams can be carried dredge mechanism of any preferred type.

The front member 3 of the main frame 70 has mounted at its extreme ends the stud shafts 6 upon which are swingingly mounted the bell crank levers 7 having mounted on their lower arms the rollers 8.

Auxiliary skids 9, having channel irons 75 10 on their upper surface, are located on each side of the main skids 1 and said channel irons 10 form tracks, which the rollers 8 of the bell crank levers 7 are adapted to 80 traverse.

A shaft 11 is mounted on two of the beams 5 and receives two members *a* and *b* which are loose thereon and adapted to be independently driven in any well known manner. The member *b* has a sprocket 85 wheel 13' connected therewith and the member *a* has a sprocket wheel 13 and a brake drum 12 connected therewith. The sprocket wheels 13 and 13' are of different diameters.

Mounted between the same two beams supporting the shaft 11, is a shaft 14 upon which is loosely mounted a sleeve 15 to which is secured the sprocket wheel 16 connected by a chain 17 to the sprocket wheel 13 and adapted to be driven thereby. A 95 sprocket wheel 16' is secured to the shaft 14 and is adapted to be driven by a chain 17' from the sprocket wheel 13'.

Two drums 18 and 18^a are loosely mounted on the sleeve 15 and may be jointly or separately rotated with the sleeve 15 by throwing either or both into engagement with a clutch member 19. The two drums are positioned on the sleeve 15 by means of collars 20 and are provided with corrugated recesses 21 which receive the corrugated periphery 22 of the clutch member 19, thereby securely locking the clutch member 19 and the drums together. The drums 18 and 18^a are thrown into and out of engagement with 105 110

the clutch 19 by means of the lever arms 23 connected to shafts 24, 24' which shafts are operated by means of levers 25 and 26.

On the outer end of the shaft 14 is mounted a pinion 27 meshing with a pinion 28 secured to a shaft 29 rotatably mounted between three of the beams 5. Loosely mounted on the shaft 29 are two sets of drums 30 and 30^a and 31 and 31^a similar in structure 10 to the drums 18 and 18^a. A clutch member 32 similar in structure to the clutch member 19 is mounted between each set of drums 30, 30^a and 31, 31^a. The drums 30 and 30^a are connected by lever arms 32^a to a shaft 33, 15 while the drums 31 and 31^a are connected by lever arms 34 to a shaft 35. The shafts 33 and 35 are operated by levers 36 and 37, respectively.

Cables 38, 38^a are attached to the upper 20 ends of the bell crank levers 7 and extend around pulleys 39 and 39^a mounted on each end of the main frame member 4, thence around pulleys 40 and 40^a mounted on the under side of the main frame member 4 intermediate the ends thereof, and then attached to the drums 18 and 18^a, respectively, upon which they are adapted to be wound or unwound.

Cables 41 and 41^a are attached to the auxiliary skids 9 and extended rearward around pulleys 42 and 42^a, mounted on each end of the main frame member 4; thence around pulleys 43 and 43^a mounted on the under side of the main frame 4 intermediate the 35 ends thereof, and then attached to the drums 31 and 30^a respectively, upon which drums they are adapted to be wound or unwound.

Attached to the skids 9 are cables 44 and 44^a extending forwardly around pulleys 45 and 45^a mounted on the front ends of the main skids 1, thence around pulleys 46 and 46^a mounted intermediate the ends of the main skids 1, thence around pulleys 47 and 47^a mounted on one of the beams 5 and then 45 attached to the drums 30 and 31^a upon which the said cables are adapted to be wound or unwound.

When it is desired to move my supporting device together with the dredging or other mechanism carried thereby, forward, it is only necessary to apply power to rotate the members *a* and *b*. This rotates the wheels 13 and 13' and through the medium of the chains 17 and 17', the sprocket wheels 16 and 16' are rotated, thereby rotating the shaft 14 and the sleeve 15 and through the instrumentality of the pinions 27 and 28, also rotating the shaft 29. The levers 25 and 26 are then operated to clutch the drums 18 and 18^a into engagement with the clutch member 19, whereupon the said drums are rotated and the cables 38 and 38^a, attached to the bell crank levers 7, are wound thereon, causing a pivotal movement of the levers 7 around the shafts 6 and thereby raising the

main skids 1, together with the frame to the position shown in Fig. 3. The power is now disconnected from the member *a* in any desired manner and the brake applied to the drum 12 to hold the levers 7 in the position indicated in Figs. 3 and 4. Next, by operation of the levers 36 and 37 the drums 30^a and 31 are thrown into engagement with the clutch members 32 and upon these drums being rotated the cables 41 and 41^a, attached to the auxiliary skid 9, are wound thereon, causing the main skids and all parts thereon to move forward on the rollers 8 which ride on the upper surface of the channel irons 10, until they have reached the extreme forward 80 end of the auxiliary skids 9. The brake 12 is then released and the main skids are free to settle to a stationary position on the surface of the ground. The drums 30 and 31^a are next clutched to the members 32 by 85 means of the levers 36 and 37 and this operation causes the said drums 30 and 31^a to rotate, causing the cables 44 and 44^a, attached to the auxiliary skids 9, to be wound thereon, thereby moving the auxiliary skids 9 forward to a position in front of the main skids 1. From the above movements it will be seen that the support together with all mechanism carried thereby, has been moved forward approximately the length of the 95 auxiliary skids 9, and upon repeated operations of the above movements, the said support can be moved forward as far as desired.

The line of travel of the machine may be 100 reversed and made to move in a backward direction by the mere reversal of the operations described above. When this backward motion is desired, the cables 41 and 41^a, attached to the auxiliary skid 9, are 105 wound on the drums 31 and 30^a, causing the auxiliary skids 9 to move backward throughout their whole length. The cables 44 and 44^a also attached to the auxiliary skids 9 are then wound on the drums 31^a and 30, causing the main skids and frame to move backward the length of the auxiliary skids 9, the rollers 8 riding in the track provided by the channel irons 10. By the addition of two 110 wheels set on stud shafts, and carried by the frame member 3, the backward movement of the support could be expedited and accomplished much easier.

From the foregoing it is obvious that I have provided a support having a positive 120 lifting and moving motion in either direction at the will of the operator and one which eliminates a great deal of delay in moving from one position to another after the machine carried by the support, has completed the work.

What I claim is:

1. In a device of the character described, a pair of spaced main skids, a pair of auxiliary skids spaced from and adjacent the

- outer sides of the main skids, a frame mounted on said main skids, stud shafts mounted in the ends of said frame, pulleys mounted at each end of the main skids, a bell crank lever mounted on each stud shaft at each end of the frame directly over the respective auxiliary skid, a roller carried by each bell crank lever and adapted to ride on the respective auxiliary skid, cables for moving both pairs of skids with relation to each other, cables for operating said bell crank levers and raising said frame to lift said main skids at their forward ends, and means for operating said cables. 5
2. In a device of the character described, a pair of spaced main skids, a pair of auxiliary skids spaced from and adjacent the outer sides of the main skids, a frame mounted on each end and at the middle of 10 said main skids, a bell crank lever mounted at each end of said frame and over-hanging the auxiliary skids, a roller carried by the bell crank levers and adapted to ride on the auxiliary skids, cables attached to the auxiliary skids for moving both pairs of skids with relation to each other, said cables running forward and rearward around the pulleys, cables running rearward around the pulleys for operating said bell crank levers 15 and raising said frame and said main skids, and means for operating said cables. 20
3. In a device of the character described, a pair of main skids, a pair of auxiliary skids spaced from and arranged adjacent the outer sides of the main skids, a frame mounted on said main skids, a pair of bell crank levers mounted on said frame and overhanging the auxiliary skids, rollers mounted on said levers and adapted to ride 25 on the auxiliary skids, cables for moving both pairs of skids with relation to each other, cables for operating said bell crank levers for raising the forward ends of said main skids, a plurality of shafts mounted 30 on the frame, a plurality of drums on said shafts, and mechanism for winding and unwinding said cables on said drums. 35
4. In combination, a frame, skids spaced from and located adjacent the outer sides 40 of the frame, lifting means mounted 45
- slightly in advance of the center of gravity of the machine and adapted to travel upon said skids, whereby the frame is lifted at two points only and whereby the machine when moving forwardly drags the rear end 55 of the frame, means upon the frame for operating said lifting means to bring the lifting means into engagement with the skids and elevate the frame, and other means upon the frame for alternately advancing said frame and said skids. 60
5. In combination, a frame adapted to rest upon the ground, auxiliary supporting means therefor adapted to travel on the ground, lifting means mounted on said frame slightly in advance of the center of gravity of the machine and adapted to travel upon the auxiliary supporting means, whereby the frame is lifted at two points only and whereby the rear end of the frame 65 is dragged along the ground as the machine moves forwardly, said supporting means being arranged on opposite sides of the frame adjacent the outer edges of the frame, means for alternately throwing the lifting means 70 into and out of engagement with the auxiliary supporting means and means for alternately advancing the said frame and auxiliary supporting means. 75
6. In a device of the character described, a pair of spaced main skids, a pair of auxiliary skids spaced from and arranged adjacent the outer sides of the main skids, a frame mounted on said main skids, pulleys mounted at each end of the main skids, a bell 80 crank lever mounted at each side of said frame and overhanging the respective auxiliary skids, a roller carried by each bell crank lever and adapted to ride on the respective auxiliary skid, cables for moving both pairs 85 of skids with relation to each other, cables for operating said bell crank levers and raising either or both sides of said frame to lift the main skids at their forward ends, whereby the main skids may be lifted at either or 90 both sides at their forward ends, and means for operating said cables. 95

In testimony whereof I affix my signature.

CARL F. WILSON.
